UNITED STATES PATENT OFFICE.

PAUL ARBON, OF TULSA, OKLAHOMA, ASSIGNOR TO RICHARD GUIBERSON, OF TULSA, OKLAHOMA.

SAND-TRAP.

1,327,583.

Specification of Letters Patent.

Patented Jan. 6, 1920.

Application filed April 21, 1919. Serial No. 291,582.

To all whom it may concern:

Be it known that I, PAUL ARBON, residing at Tulsa, in the county of Tulsa and State of Oklahoma, a subject of Great Britain, 5 have invented or discovered certain new and useful Improvements in Sand-Traps, of which improvements the following is a specification.

The presence of float sand in most oil 10 wells is the cause of considerable labor and expense in the pumping of the oil, as the sand after being carried past the foot valve at the bottom of the tubing will settle down around the valve and retard or wholly prevent further flow of oil into the tubing. 15 When the valve recesses are thus clogged, it is necessary to pull the sucker rods and the tubing to remove the accumulated sand. The labor and loss of production render this 20 operation very expensive to the producer.

The object of the invention described herein is to provide means for trapping a large percentage of the sand carried past the foot valve, and also to provide for the removal of the foot valve with the working barrel when the operation of the valve is interfered with by an accumulation of sand. The invention is hereinafter more fully described and claimed.

30 In the accompanying drawing forming a part of this specification is shown in sectional elevation the lower portion of the tubing for a well having combined therewith the improvements claimed herein.

35 In the practice of the invention a trap chamber is connected to the lower end of the tubing 1 at a point below that portion of the tubing in which a pump barrel 2 of the usual or any suitable construction operates.

40 This trap chamber is formed by a section of tubing 3 preferably of a diameter substantially greater than that of the tubing 1 and having its end portions swaged down so that they may be connected to the lower

45 end of the tubing 1 and to the anchor tube 4 by coupling sleeves 5 and 6. The coupling 5 is of the type usually employed for connecting the tubing sections, but the coupling 6 is provided with a diaphragm 7 having an opening therethrough to permit of

50 the flow of oil from the anchor tube. The edges of the opening are shaped to form a seat for the lower end of a hollow plug 8 which is connected by a threaded sleeve 9

to the lower end of tube section 10 having 55 an external diameter less than the internal diameter of the tubing 1. The foot valve consists of a ball or movable member 11 and a seat 12 which is supported by the plug 8. In order to hold the ball in operative relation to the valve seat, a pin 13 is passed through the tubing section 10 a short distance above the ball. A rod 14 having its upper end connected by a yoke 15 to the pump barrel 2 extends down into the tubing 60 10 a distance greater than the range of movement of the pump barrel when operated to remove oil from the well. On the lower end of the rod is screwed a head 16 so constructed as to permit the flow of oils 70 past it but adapted to engage the shoulder 17 and the upper end of the tubing section so that the latter and the foot valve may be withdrawn from the well with the pump 75 barrel. The tube section is perforated adjacent to its upper end to permit the flow of oil into the trap chamber.

It is characteristic of the improvement described and claimed herein that as the tube section 10 is substantially smaller than 80 the tubing 1 the oil will flow with sufficient velocity through the tube section to carry a very large percentage of sand into the trap chamber in which the sand will have an opportunity to settle on account of its 85 diameter being greater than that of the tubing and its length greater than the range of the pump barrel.

As the greater portion of the sand will pass into the trap chamber, the accumulation 90 of sand in the bottom of the tube section 10 will be slow and when the valve becomes clogged the tube section with the foot valve can be withdrawn through the tubing 1 which need not be pulled. 95

I claim herein as my invention:

1. In an apparatus for pumping wells the combination of a trap chamber adapted to be connected to the tubing and anchor tube, a movable tube section of less diameter than 100 the tubing of the well and projecting up into the trap and adapted to discharge into the trap, a check valve carried by the tube section and means whereby the tube section may be connected to the working barrel of the 105 well.

2. In an apparatus for pumping wells the combination of a trap section having a

greater internal diameter than the tubing, means for connecting said chamber to the tubing, and the anchor section, a removable tube section of less diameter than the internal diameter of the tubing and projecting up into the trap chamber, a check valve carried by the removable tube section, a mov-

able rod adapted to engage the removable section and adapted to be connected to the working barrel of a well.

In testimony whereof, I have hereunto set my hand.

PAUL ARBON.
